UNITED STATES PATENT OFFICE.

STILLMAN W. ROBINSON AND ORLANDO E. LEWIS, OF COLUMBUS, OHIO.

MACHINE FOR UNITING SOLES AND UPPIERS.

SPECIFICATION forming part of Letters Patent No. 319,127, dated June 2, 1885.

Application filed September 29, 1884. (No model.)

To all whom it may concern:

Be it known that we, STILLMAN W. ROBINSON and ORLANDO E. LEWIS, both of Columbus, county of Franklin, and State of Ohio, have 5 invented an Improvement in Machines for Uniting Soles and Uppers, of which the following description, in connection with the accompanying drawings, is a specification, like letters on the drawings representing like parts.

10 In the manufacture of boots and shoes wherein the sole-fasteners are automatically driven through the sole and upper it is customary, especially when metallic fasteners have been used, to last the boot or shoe on a last, then 15 withdraw the last preparatory to placing the boot or shoe upon a horn for the reception of the sole-fasteners, and after the fasteners have been inserted or driven the boot or shoe removed from the horn has been again placed 20 upon a last to be finished. Desiring to obviate the expense attendant upon removing the last from the boot or shoe between the lasting operation and that of driving or inserting the sole-fastenings, and also to finish or tree the 25 shoe on the last upon which it was lasted, we have produced a hollow metal shell-like last upon which the boot or shoe may be lasted, and thereafter by the removal of the last-block the hollow last may be applied to the horn of 30 a nailing-machine, the last being moved about on the surface of the horn while the sole-fastenings are being inserted. In the manufacture of boots and shoes by machinery having a horn either the tip of the horn or the nose 35 is always brought to a definite position, while the other yields to adapt itself to the thickness of the stock being worked upon, and the member which is thus variable as to its position usually automatically controls the length 40 of the fastener to be driven, especially if a wire is used. In this instance we have shown our improvement applied to a horn the top of which is supposed to always stand at a defined level while the fastener is being inserted, the 45 horn being, for instance, such as represented in United States Patent No. 297,718, dated April 29, 1884, wherein the horn always occupies the same position while the fastener is being inserted, and wherein the nose rises and 50 falls to adjust itself to the thickness of the stock and to vary the length of the fastening.

The hollow or shell-like last upon which the boot or shoe is lasted, and which last is applied to the horn while the shoe is upon it, is so chambered as to permit the horn to pass 55 into the last and have its tip presented with reference to the sole and upper just as when the boot or shoe is applied directly to the last, and to prevent the last from interfering with the production of fasteners of the proper 60 length we have found it essential to make that part of the last which comes directly in contact with the tip of the horn of uniform thickness, so that the bottom of the last, supported by the horn, will always come to a certain definite height, just as when the horn was used alone. The ends of the fasteners being inserted, meet the bottom of the metal last, the horn merely supporting the last.

Figure 1, in side elevation and partial section, represents a sufficient portion of a machine for uniting soles to uppers to enable our invention to be understood; Fig. 2, a partial view of the last and its block, the latter being held in place. Fig. 3 is a side elevation of 75 the last, partially broken out to show the devices for retaining the block in position with relation to the body of the last.

The rotating horn H is substantially the same as in other nailing-machines heretofore 80 employed in boot and shoe work—as, for instance, in United States Patent No. 297,718.

The body A of the last is made to represent a thin last-shaped shell, the bottom b of which, along each edge of the last from heel to toe 85 and about the toe and heel, as shown by section and dotted lines, Fig. 1, is of substantially uniform thickness, so as to always present in all positions of the last upon the tip of the horn, and while the last is moved longitudinally and rotated on the said tip, the same amount or thickness of material. The block c of the last, provided with the usual prong or catch, c', and with projections c' to pass into the body of the last to assist in holding the block securely in place thereon, is made longer than heretofore in metal lasts, so that ample room is left for the reception and rotation of the horn when the block is removed from the last, the block being retained 95 chiefly by the block-locking device d, (shown as a latch pivoted at d'.) The upper and sole 100

of the boot or shoe to be made having been lasted upon the last composed of the body A and block c, and the outer sole having been tacked upon the lasted boot or shoe, the block 5 c is withdrawn and the last-body with the shoe or boot yet upon it is placed on the horn H, the tip of the horn acting as a support for the inner side of the bottom of the last as the latter is moved longitudinally on the horn. 10 The fasteners having been inserted, the last, with the shoe or boot yet on it, is removed from the horn, the block c is again inserted in the boot or shoe, and the upper and sole are thereafter finished in the usual manner, after 15 which the last is placed upon the pin of a jack, the last having a hole, 3, made therein for such purpose, and the heel is applied in usual manner. By not removing from the boot or shoe the last upon which it was lasted 20 until after the sole and upper have been permanently secured and the sole finished, the boot or shoe is kept in its original shape instead of being stretched out of shape, as is apt to be the case when the boot or shoe in 25 the process of its manufacture is applied to first one and then another last and is entirely removed from a last when the sole and upper are being united in a railway-machine while held by hand. The operator will move the 30 last and shoe on the horn, and will partially rotate the horn, just as he formerly moved the lasted shoe after removing the last. The last is entirely unobstructed at the inner side of

its bottom from edge to edge, so that the last may be freely moved on the horn. 35

I claim—

1. The hollow metallic shell-like last cut away substantially as shown and described, whereby the top of the horn may have a bearing entirely around the toe portion of the last, 40 substantially as described.

2. The hollow metallic shell-like last having the chamber for the reception of the horn, and provided with the hole 3 and the block, to operate substantially as described. 45

3. The hollow metallic shell-like last having its bottom of uniform thickness where the same rests upon the tip of the horn, substantially as and for the purpose described. 50

4. The combination, with a horn, of the hollow metallic shell-like last cut away to permit the entrance of the tip of the horn into the toe of the last opposite the point at which the sole-fasteners are to be inserted, substantially as described. 55

In testimony whereof we have signed our names to this specification in the presence of two subscribing witnesses.
